KNOCKOFF MOTION FOR DRAWING
MACHINESErvin M. Dunn and John C. Baucom,
Concord, N. C.

Application May 27, 1942, Serial No. 444,714

2 Claims. (Cl. 19—167)

This invention relates to a knock-off motion for drawing machines as used in connection with the spinning of cotton or other fibers.

It is particularly aimed to provide an exceedingly simple construction capable of serving as an attachment for existing machines, one which is adapted for adjustable mounting on the table or frame of the drawing machine and one which employs an adjustable stop or ratchet on the rocker means which controls operation. The invention prevents waste of cotton and calender rolls caused by lumps catching in trumpets, by stopping the machine. The machine will also be stopped by any extraneous matter which passes between the upper and lower rolls. Use of the invention will step up production, will prolong the life of cork or leather that is used on some rolls and will reduce injury on steel or metallic rollers.

The more specific objects and advantages will become apparent from a consideration of the description following taken in connection with accompanying drawings illustrating an operative embodiment.

In said drawings:

Figure 1 is a fragmentary view in end elevation for the most part, the drawing machine table being shown in section;

Figure 2 is a vertical section through the parts of Figure 1 taken at a right angle thereto;

Figure 3 is a vertical sectional view detailing the stop or ratchet device employed on the rocker means;

Figure 4 is a detail plan view of the stop or ratchet element alone;

Figure 5 is a substantially central vertical sectional view through the pivotal mounting for the knock-off lever;

Figure 6 is a plan view of said knock-off lever and mounting, and

Figure 7 is a detail perspective view, partly broken away, of one of the control bars employed.

Referring specifically to the drawings wherein like reference characters designate like or similar parts, sufficient elements of a drawing frame such as is employed in connection with the spinning of cotton or other fibers, is shown generally at 10, to enable our invention to be illustrated and understood. Our invention is shown as an attachment for the machine although it may be built into the same initially if desired.

Of the said drawing machine 11 represents a series of upper rolls coacting with a series of lower rolls 12 between which the cotton or other fibers pass as is conventional. The rollers 11 are

relatively loose so that they may move vertically away from the rolls 12 independently of each other. The table of the drawing machine is fragmentarily suggested at 13, and means for operating the rollers as is conventional in the art, is under control of rocker means which may be in the form of a shipper lever 14 carrying a shaft, which rocks with the lever, at 15. Elements 15 continuously oscillates when the drawing frame is running and this element is known as the rocker shaft of the drawing frame. In practice, the rolls 11 are sometimes entirely of steel, sometimes are provided with external surfaces of leather, cork or other material. Our invention is capable of use regardless of the material from which the rollers are made, particularly the rollers 11, and it coacts with the rollers regardless of the material used in their manufacture.

In carrying out the invention, we provide a knock-off mechanism including one or more knock-off levers at 16, preferably two being employed as illustrated best in Figure 1 and the same being arranged on opposite sides of the path traversed by the cotton or fibers coacting with the rollers 11 and 12. Said levers 16 are pivoted by means of horizontal bolts at 17 to heads 18 of screw shanks 19 integral therewith. Such screw shanks 19 pass through openings 20 in the table 13 and such shanks are rigidly fastened at any desired elevation by nuts 21, threaded thereto and coacting with opposite sides of table 13, preferably with washers 22 interposed. Such construction enables the height of the knock-off levers 16 to be varied, or adjusted.

Levers 16 have hooks 23 at one end, adapted for interlocking engagement with the upper end of a stop element 24 which may be of metal and have its upper end curved outwardly as at 25. The stop element 24 is also preferably vertically adjustable for coaction with the hook 23. Element 24 is carried by a sectional clamp 26. Clamp 26 may be made in two parts or blocks 27 which are rigidly secured removably to the shaft 15. Such blocks are held in place by bolt or screw members 28 and the latter pass through enlarged slots 29 of the stop element 24, to secure the latter in place adjustably as described. A set screw 30 may also pass through one of the blocks 27 for binding engagement against the shaft 15.

Knock-off levers 16, if unrestrained, will move downwardly at their hook ends 23 and engage the stops 24 at the portions 25, thus arresting motion of the shipper lever 14 or other control means. However, during normal operation of the drawing frame, the knock-off levers do not interfere

with the operation of the shipper lever or rocker means since we provide control bars or members 31 which rest across the top of the rolls 11, being transverse with respect to their axes, and being held in place by dependents 32 thereon, passing between certain of the rolls as shown and engaging the levers 16 at the ends opposite to the hooks 23, the weight of the control members being such as to normally sufficiently depress the levers 16 at their adjacent ends, as to maintain the hooks 23 out of engagement with the stops 24. However, if for any reason any of the rolls 11 should rise, at either or both ends, it will raise or tilt one or both of the bars 31 and dependent 32 thereof, thus freeing the adjacent end of the lever 16 for enabling movement thereof to such an extent that the weight of the levers between the axes 17 and hooks 23 will lower them into engagement with the stop members 24, thus throwing the rolls out of operation to stop or knock-off the power therefor.

It will be understood that the knock-off herein described will stop the machine as soon as any extraneous matter passes between the upper and lower rolls 11 and 12, which will sufficiently raise one of the rolls 11. The construction will step up production caused by machine failure to stop when lapping up, will save waste cotton or other fibers and calender rolls caused by lumps catching in trumpets and not letting the machine knock-off, will eliminate accidents caused by wrapping up, will save cork, leather or the like when one end of a roll wraps up and the other end comes in contact with the steel roll causing it to cut off the cork or leather on the latter, will save and prevent many broken steel rollers and will step up the life of cork, leather or equivalent rollers.

We claim as our invention:

1. In a knock-off motion for drawing rolls, an oscillating element, means controlling the power to operate said rolls, a knock-off lever, means on the said oscillating element engageable by the lever to prevent operation of the said oscillating element when the lever is unrestrained to stop operation of the rolls, and control means normally maintaining the knock-off lever disengaged from the second-mentioned means consisting of a control member subject to displacement by movement of one of the rolls, means pivotally mounting the knock-off lever comprising a pivot element, a screw member having a head mounting the pivot element, said screw member engaging the frame of the machine, and fastening means coating with the screw member on opposite sides of that part of the frame mounting the screw member.

2. In a knock-off motion for drawing rolls, an oscillating shaft, means controlling the power to operate said rolls, a knock-off lever, a stop element engageable by the lever to prevent operation of the said oscillating shaft when the lever is unrestrained to stop operation of the rolls, a sectional clamp, fastening means securing the clamp to the shaft, said stop element having enlarged openings, the fastening means passing through said openings and securing the stop member to the clamp, and said knock-off lever having a hook engageable with the stop element, control means normally preventing engagement of said hook with said stop element consisting of a control member subject to displacement by vertical movement of the rolls.

ERVIN M. DUNN.
